MINING MACHINE

Joseph F. Joy, Franklin, Pa., assignor to Sullivan Machinery Company, a corporation of Massachusetts

Application July 31, 1940, Serial No. 348,848

17 Claims. (Cl. 262—30)

This invention relates to mining machines, and more particularly to improvements in a coal mining machine of the combined cutting and loading type for cutting the solid coal in a mine wall and for concurrently loading the cut coal previously blasted down from the mine wall.

An object of the present invention is to provide an improved mining machine. Another object is to provide an improved mining machine for cutting and loading coal in mines. A further object is to provide an improved combined coal cutting and loading machine for simultaneously cutting the solid coal and loading the cut coal previously shot down from the solid. Yet another object is to provide an improved long-wall coal mining machine having coal loading means mounted thereon in an improved manner. A still further object is to provide an improved coal shoveling mechanism adapted for association with a coal cutting machine and mounted on the machine in an improved manner. Still another object is to provide an improved combined cutting and loading machine movable along a coal face and having kerf cutting means for cutting a horizontal kerf in the solid coal, and improved loading means for gathering the loose coal previously shot down from the coal face and for moving the loose coal so gathered onto a face conveyor arranged parallel to the coal face outside the path of movement of the machine. A still further object is to provide improved driving means for the shoveling mechanism, driven from the driving motor of the coal cutting machine. Yet another object is to provide an improved coal cutting and loading machine having an improved simplified and compact arrangement of parts whereby the dimensions of the machine are reduced to a minimum, thereby enabling the machine to operate in the relatively narrow space between the coal face and the face conveyor at the inner face side of the roof props. These and other objects and advantages of the invention will, however, hereinafter more fully appear.

In the accompanying drawings there is shown, for purposes of illustration, one form which the invention may assume in practice.

In these drawings:

Fig. 1 is a top plan view of the improved coal mining and loading machine, a portion of the machine frame being broken away to illustrate details of the internal mechanism.

Fig. 2 is a side elevational view of the machine shown in Fig. 1.

Fig. 3 is a detail vertical sectional view taken on line 3—3 of Fig. 1.

Fig. 4 is a detail vertical sectional view taken on line 4—4 of Fig. 1.

Fig. 5 is a detail vertical sectional view taken on line 5—5 of Fig. 1.

Fig. 6 is a detail vertical sectional view taken on line 6—6 of Fig. 1.

Fig. 7 is a view in longitudinal vertical section taken on the planes of line 7—7 of Fig. 1.

Fig. 8 is a cross sectional view taken substantially on line 8—8 of Fig. 7.

Fig. 9 is a detail vertical sectional view taken on line 9—9 of Fig. 7.

Fig. 10 is an enlarged detail horizontal sectional view taken substantially on line 10—10 of Fig. 7.

Fig. 11 is an enlarged detail horizontal sectional view taken substantially on line 11—11 of Fig. 7.

Fig. 12 is a somewhat diagrammatic horizontal sectional view indicating different positions of the shovel to delineate the path of movement traced by the shovel of the shovel mechanism.

Fig. 13 is a diagrammatic view illustrating the machine in coal cutting and loading position with respect to a coal face in a mine.

Fig. 14 is a diagrammatic view, similar to Fig. 13, showing the cutting and loading machine operating at an opposite coal face in a mine.

In the illustrative embodiment of the invention there is shown a coal mining machine of the combined coal cutting and loading, longwall, tractor-mounted type for cutting the solid coal and for simultaneously loading the cut coal previously shot or blasted down from the coal face. While the machine shown is of the tractor-mounted, longwall type, it will be evident that various features of the invention may be embodied in mining machines of various other types, and, if desired, the machine may be wheel mounted or may slide directly on its bottom on the mine floor.

The machine disclosed herein generally comprises a portable base, herein a machine frame 1, mounted on tractor-tread mechanism 2 and carrying kerf cutting means generally designated 3, and coal loading means generally designated 4; and a reversible motor 5 is carried by the machine frame for driving the tractor-tread mechanism and the kerf cutting and loading means, as hereinafter fully described.

The tractor-tread mechanism 2 comprises endless tractor treads 6, 6 suitably guided for circulation in guideways on tread guide frames 7 suitably secured to the sides of the machine frame. The tractor treads each comprise a series of tread plates 8 pivotally connected together by conventional strap links 9, and the tread plates

may have tooth-like projections or lugs 10 to insure proper traction during propulsion of the machine along the coal face during the cutting and loading operations. The horizontal power shaft 11 of the motor 5 (Fig. 7) extends longitudinally of the machine frame and has keyed thereto a spur pinion 12 meshing with a spur gear 13, the latter in turn keyed to a horizontal, longitudinally extending shaft 14 herein preferably arranged parallel with the motor power shaft 11. Also keyed to the shaft 14 and driven by the gear 13 is a spur pinion 15 meshing with a spur gear 16. Integral with the gear 16 and driven thereby is a bevel pinion 17, and the gears 16 and 17 are journaled on a bearing sleeve supported on the motor power shaft in coaxial relation with the spur pinion 12 in the manner shown. The bevel gear 17 meshes with coaxial, oppositely rotatable reverse bevels 18 and 19 having their hubs suitably journaled within the side walls of a gear housing 20. Arranged coaxial with these bevel gears and extending through the hubs thereof is a shaft 21, and the reverse bevels are alternately connectible to the shaft 21 by a sliding jaw clutch 22 having an operating lever 23. This clutch is splined to the shaft 21 and has clutch teeth engageable with clutch teeth on the bevel gear hubs. Keyed to the opposite ends of the shaft 21 are spur gears 24 meshing with planet gears 25, the latter in turn meshing with internal gears 26. The internal gears 26 are suitably journaled on the sides of the gear housing 20 and have external cylindric braking surfaces 27 with which conventional brake shoes 28 are engageable for frictionally resisting rotation of the internal gears. These brake shoes are provided with operating levers 29. Instead of the brake shoes disclosed, brake bands may obviously be employed, if desired. The planet gears 25 are journaled on stub shafts 30 formed integral with rotatable reaction members 31, and these reaction members have shafts 32 suitable journaled within bearings supported within the sides of the machine frame. Keyed to the outer ends of the shafts 32 are spur pinions 33 meshing with spur gears 34 keyed to aligned horizontal, transversely extending shafts 35, herein arranged parallel with the shafts 21 and 32. The shafts 35 are suitably journaled within the machine frame and have keyed thereto the hubs of drive sprockets 36 which engage and drive the endless tractor treads. It will thus be seen that under the control of the jaw clutch 22 the tractor treads may be driven through the reverse bevels in either of opposite directions, and may be independently speeded up or slowed down under the control of the brake shoes 28 frictionally engaging the braking surfaces on the internal gears 26 of the planetary gearings. It will thus be seen that the planetary gearings provide independent variable speed drives for the tractor treads, thereby to enable steering of the machine by the treads, in a manner well known to those skilled in the art.

Now referring to the kerf cutting means 3, it will be noted that pivotally mounted on a projecting portion 40 on the machine frame, on the trailing end thereof, for horizontal swinging movement relative to the frame, is an elongated plane cutter bar 41 having guided for circulation about its margin an endless cutter chain 42. Keyed to and driven by the shaft 14 is a bevel pinion 43 which meshes with and drives a bevel gear 44 having its hub suitably journaled within the projecting frame portion 40. Connectible to the hub of the bevel gear 44, by a

sliding clutch 45, is a chain sprocket 46 which engages and drives the endless cutter chain 42. The sliding clutch 45 is provided with a vertical operating rod 47 having its upper end threaded at 48 for engagement with collars 49. The collars 49 have a shipper lever 50 whereby the rod may be conveniently operated. Movement of the lever 50 effects axial movement of the operating rod 47, and, as a result, the sliding clutch 45 may be moved into its clutched position. It will thus be seen that when the sliding clutch 45 is connected the cutter chain 42 may be driven from the motor 5 through the spur gearing 12, 13, shaft 14, bevel gearing 43, 44, and the drive sprocket 46; and when the sliding clutch is disconnected, the cutter chain may remain idle during running of the motor.

Now referring to the improved loading means 4, it will be noted that pivotally mounted on vertical axes at the advancing end of the machine frame, within the vertical limits of the latter, are vertical, oscillatory shovel plates 51 and 52, each having a toothed forward portion 53 to facilitate penetration of the loose coal to be loaded. Each of these shovel plates 51, 52 has formed along its upper and lower edges longitudinal guideways 54 and 55 which slidably receive the upper and lower edges of vertical retaining and guiding plates 56 and 57. The plates 56 and 57 accordingly have sliding telescopic relation with the shovel plates, and are pivotally mounted on vertical axes at 58 and 59 respectively, near the opposite sides of the machine frame. The shovel plates 51 and 52 are hinged together at 60, near their outer adjacent ends, on a vertical hinge pin 61, the latter being secured at its ends within brackets 62, in turn suitably secured to upper and lower arms 63 and 64. These arms extend rearwardly respectively near the tops and bottoms of the shovel plates and are pivotally connected to the shovel plates on an axis coincident with the hinge pivot 60; and in this instance the hinge pin 61 provides the pivotal connection between the shovel plates and the arms. Extending vertically between the arms is a tie bolt 65; and a tubular spacing sleeve 66 surrounding the tie bolt is interposed between the arms, with its ends abutting the inner arm surfaces to maintain the arms in proper spaced relation. The arms 63 and 64 are pivotally connected at 67 to crank discs 68 and 69, respectively arranged at the top and bottom of the machine frame; and these crank discs have crank pins 70 to which the arms are pivotally connected, so that when the crank discs are rotated the arms are actuated to effect swinging movement of the shovel plates 51 and 52 about their pivots. Each of the arms has a rearwardly extending guide rod 71 slidably guided at 72 within a swiveled guide member 73 journaled at 74 within the upper and lower portions of the machine frame. The upper guide member 73 is preferably journaled within a detachable bracket 75. Referring again to the hinge connection 60 between the shovel plates, it will be noted that the shovel plate 51 has secured thereto hinge brackets 76 engaging the hinge pin 61, and the shovel plate has laterally offset or bent portions 77 providing slots 78 which receive the inner portions 79 of the hinge brackets when the shovel plate is in its retracted position. The shovel plate 52 has integral hinge brackets 80 which likewise engage the hinge pin 61 in the manner shown in Fig. 10. The teeth on the toothed penetrating edges of the shovel plates are preferably arranged in staggered rela-

tion, in the manner shown in Fig. 2, so that the teeth on one plate may swing within the spaces between the teeth on the other plate as the shovel plates are actuated to effect their shoveling function.

The means for driving the shovel mechanism, as shown in Figs. 7 and 9, comprises a vertically disposed tubular shaft 82 journaled at its lower end within the hub of the bevel gear 44, in coaxial relation with the latter, and at its upper end within the hub of a chain sprocket 83. The shaft 82 is connectible to the bevel gear 44 by a sliding jaw clutch 84 splined to the shaft 82 and having clutch teeth engageable with clutch teeth on the bevel gear hub. The chain sprocket 83 has a hub journaled at 85 within the machine frame, and a collar 86 secured to the chain sprocket hub maintains the sprocket in position within its bearing. Surrounding the shaft 82 and interposed between the jaw clutch 84 and the collar 86 is a coil spring 87 which constantly urges the jaw clutch toward its lowermost clutched position. The jaw clutch is releasable against the tension of the coiled spring by means of a vertical operating rod 88 guided for axial sliding movement within the machine frame and having its threaded upper end 89 engaging a nut 90. The nut rotatably engages a bracket 91 secured to the machine frame, and has a conveniently located operating handle 92. When the nut is rotated the operating rod may be moved vertically upwardly to effect clutch release, thereby to disconnect the chain sprocket 83 from driven relation with the bevel gear 44. As illustrated, the chain sprocket 83 is connected by an endless drive chain 93 extending through the upper portion of the machine frame, to a chain sprocket 94, herein formed integral with the upper crank disc 68. As shown in Fig. 7, the crank discs are keyed to a vertical shaft 95 suitably journaled within the machine frame, so that the upper crank disc may effect drive, through the shaft 95, of the lower crank disc 69. It will thus be seen that when the jaw clutch 84 is connected the shovel mechanism may be driven by the motor 5 through the spur gearing 12, 13, shaft 14, double gearing 43, 44, clutch 84, shaft 82, chain sprocket 83, drive chain 93, chain sprocket 94 and the crank discs 68, 69, and arms 63 and 64.

As is usual in coal mining machines of the longwall type, the cutter bar 41 may be swung about its pivot from a position extending lengthwise of the machine frame, to right-angle positions at either side of the machine frame, and the cutter bar has a conventional hanger frame, indicated in dotted lines at 96 in Fig. 7, which engages the projecting portion 40 of the machine frame; and carried by the hanger frame is a locking device 97, such as a friction clamp, for locking the cutter bar in any of its adjusted positions. Mounted on the top of the machine frame along one side of the latter is a guide bar 100 having a vertical flange 101 engageable with the coal face for guiding the machine during movement of the latter along the coal face during the cutting and loading operations. This guide bar has inwardly bent ends 102 to facilitate movement thereof along the coal face, and the horizontal overlying portion 103 of the guide bar is provided with transverse slots 104 through which tightening screws 105 threaded within the top of the machine frame, pass. These slots permit lateral adjustment of the guide bar with respect to the machine frame into engagement with the coal face, and the screws 105, when tightened,

firmly secure the guide bar in position. As above mentioned, the machine is capable of cutting and loading at either of opposite coal faces; and when the cutter bar is disposed in its opposite position to effect cutting and loading along the opposite face the motor 5 may be reversed and the cutter bits reversed on the cutter chain, in a manner well known to those skilled in the art.

Pivotedly mounted on axes coincident with the pivotal axes 58 and 59 for the shovel guide plates 56 and 57 respectively, are vertical deflector plates 107 and 108; and when the machine is operating to effect its cutting and loading functions, with the guide bar 100 in engagement with the coal face, the inactive deflector plate 107 nearest the coal face is folded inwardly against the side of the machine, in the manner indicated in dotted lines in Fig. 1. The active deflector plate 108 at the side of the machine remote from the coal face may be swung outwardly into the position shown in Fig. 1, and held in such position by means of a brace rod 109 pivotally connected at 110 to the adjacent side of the machine frame. This brace rod has sliding telescopic engagement with a tubular member 111 pivotally connected at 112 to the deflector plate. As the deflector plate 108 is swung laterally into its different adjusted positions with respect to the side of the machine frame, the rod 109 telescopes with respect to the member 111, and when the parts are properly adjusted a screw 113 may be tightened to hold the parts in adjusted position. The deflector plate 107 has a similar brace rod arrangement.

As the machine moves along the coal face to effect its cutting and loading operation, the shovel mechanism gathers the loose coal previously shot down on the mine floor adjacent the coal face and moves the loose coal laterally away from the coal face out of the path of movement of the machine, and the deflector plate 108 deflects the coal, as it is discharged from the shovel mechanism, in a lateral direction away from the machine. In this instance, the deflected coal is received by a conventional face conveyor 114 laid on the mine floor between the machine and the roof props at the side of the machine remote from the coal face, and this conveyor may move the loose coal away from the machine to a suitable point of disposal. The conveyor 114 is shown diagrammatically in Figs. 13 and 14 and is preferably of an extremely low compact design. When the motor of the mining machine is reversed to effect reversal of the drive of the cutter chain and is operating along the opposite coal face as shown in Fig. 14, the shovel plates of the shovel mechanism reverse automatically so that the shovel mechanism may act to gather the loose coal and move it laterally in the opposite direction. During cutting and loading along the opposite coal face, the guide bar 100 is removed from the machine frame and transposed to the opposite side of the machine frame in an obvious manner, and the opposite side of the machine frame is provided with threaded apertures to receive the bar holding screws 105. At that time the deflecting plate 108 is swung inwardly into an out-of-the-way position beneath the guide bar and the deflector plate 107 is extended.

While certain of the operating handles or levers for the various clutch and brake operating devices are shown projecting above the top of the machine frame, it will be evident that, if desired, these levers and handles may be located at the ends or sides of the machine frame beneath the

top of the latter, thereby to lower the height of the machine when it is desired to operate the machine in mines having low head room. Such lever and handle arrangements are well known in machines of this character, and therefore illustration thereof is unnecessary. It will further be noted that portions of the operating mechanism are illustrated in a somewhat simplified form, and that changes in proportions to handle heavy loads may be made without departing from the present invention.

The mode of operation of the improved cutting and loading machine will be clearly apparent from the description given. When the mining machine is being moved about the mine under the propulsion of the track-laying treads, the shovel mechanism is preferably in its centrally located position and the cutter bar is disposed lengthwise of the machine, as indicated in dotted lines in Fig. 1. As the machine is propelled about the mine by the tractor-tread mechanism it may be steered by varying the relative speeds of the planetary gearings 24, 25, 26 under the control of the brake shoes 28, it being possible by speeding up the drive of one tractor tread and slowing down the drive for the other to effect turning movements of the machine in a well known manner. When the working face is reached and the machine is disposed in either of the positions shown diagrammatically in Figs. 13 and 14, the cutter bar may be manually swung laterally from its longitudinal position to the full-line position shown, at right angles to the length of the machine frame, and may be locked in this position by the locking device 97. The sliding clutch 45 may then be connected, thereby to connect the cutter chain in driving relation with the motor, and as a result the cutter chain may be rapidly circulated about the margin of the cutter bar. If desired, the cutter bar may be swung horizontally beneath the coal at a cutting speed under the control of the track-laying treads, this being accomplished by holding one of the treads against movement while the other is driven to effect such swinging movement. When the cutter bar is in sumped position beneath the coal face and the cutter chain is rapidly circulated, the clutch 84 may be connected to connect the shovel mechanism in driving relation with the motor, and the machine may then be fed bodily rectilinearly along the coal face under the control of the planetary gearings of the tractor-tread mechanism. As the machine moves along the coal face, the cutter chain cuts a horizontal kerf in the coal near the level of the mine floor while the shovel mechanism gathers the loose coal previously shot down from the coal face on the mine floor and moves the loose coal, with a lateral shoveling action, out of the path of the machine and toward the face conveyor 114, and the active deflector plate deflects the coal onto the face conveyor. As the machine moves bodily along the coal face the toothed outer ends of the shovel plates penetrate the loose coal and the then-active shovel plate gathers the loose coal and moves the loose coal in a lateral direction away from the coal face. When it is desired to effect cutting and loading along an opposite coal face, the cutter bar may be swung into the right-angle position shown in Fig. 14, and upon reversal of the motor and reversal of the cutter bits on the cutter chain the machine may be propelled along the coal face to effect cutting and loading in the reverse direction, the shovel mechanism at that time gather-

ing the loose coal and moving the loose coal with a lateral shoveling action in the opposite direction. Of course, at that time the face conveyor 114 is disposed in the opposite position, at the side of the machine remote from the coal face, in the manner shown in Fig. 14. As previously described, when the position of the machine is reversed with respect to the coal face, the guide bar 100 is transposed to the opposite side of the machine. Also the shovel plates may be inverted and reversed.

In Fig. 12 the shovel plates 51 and 52 are shown in different gathering positions as indicated at A, B, C and D (the latter three positions being indicated in dotted lines) and the outer edge of the active shovel plate traces an orbit as delineated by E in dot and dash lines in Fig. 12. Other modes of use and advantages of the improved mining and loading machine will be clearly apparent to those skilled in the art.

As a result of this invention an improved mining and loading machine is provided which is adapted concurrently to undercut and load the coal in accordance with the longwall system of mining. Furthermore, it will be noted that by the provision of the improved shovel mechanism and the improved manner of mounting the shovel mechanism on the mining machine, loading of the loose coal is effected in an improved manner. It will also be evident that by the provision of the improved cutting and loading machine and its novel arrangement of parts, extreme compactness is possible; and further, due to the relatively simple construction, ruggedness is obtained.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a combined cutting and loading machine, the combination comprising a portable base arranged parallel to and movable bodily rectilinearly along a coal face, kerf cutting means carried by said base for cutting a kerf in the coal, and coal loading means including coal loading devices carried by said base at the advancing end thereof and embodying an oscillatory loading member movable horizontally back and forth with respect to said base for moving the loose coal in the machine path across the forward end of the machine and laterally away from the side of the machine remote from the coal face, said kerf cutting means and said coal loading means acting concurrently to cut and load the coal as the base moves bodily along the coal face.

2. In a mining and loading machine, the combination comprising a portable base movable along a coal face, kerf cutting means carried by said base comprising a kerf cutter projecting laterally from the side of said base near the coal face, and coal loading means carried by said base at the advancing end thereof and including gathering and loading devices confined to horizontal movement back and forth across the advancing end of said base near the level of the mine floor for gathering the loose coal in the machine path and moving the same laterally beyond the side of said base remote from the coal face to clear the machine path, said kerf cutting means and said loading means acting concur-

rently to cut and load the coal along parallel paths as the machine moves bodily along the coal face.

3. In a mining and loading machine, the combination comprising a portable base movable along a coal face, kerf cutting means carried by said base comprising an elongated plane kerf cutter projecting laterally at right angles from the rear trailing end of said base, and loading means carried by said base at the forward advancing end thereof and including gathering and loading devices for gathering the loose coal on the mine floor in advance of the machine and moving the loose coal laterally out of the path of movement of said base, said gathering and loading devices including a vertical shovel element pivotally mounted on the advancing end of said base within the vertical limits of the latter and swingable horizontally across the forward end of said base.

4. In a mining machine of the character described, the combination comprising a portable base movable along a coal face, and shovel mechanism mounted on the forward end of said base within the vertical limits of the latter comprising a pair of cooperating shovel plates hinged together near their outer ends and means for swinging said shovel plates to move the material to be gathered laterally out of the path of movement of said base.

5. In a mining machine of the character described, the combination comprising a portable base movable along a coal face, shovel mechanism mounted on the forward end of said base within the vertical limits of the latter comprising a pair of cooperating shovel plates hinged together near their outer ends, a pair of cooperating guide plates pivotally mounted on said base and having sliding engagement with said shovel plates, said shovel plates having guideways for slidingly receiving said guide plates, and means for swinging said guide and shovel plates to move the material to be gathered laterally out of the path of movement of said base.

6. In a mining machine of the character described, the combination comprising a portable base movable along a coal face, shovel mechanism mounted on the forward end of said base within the vertical limits of the latter comprising a pair of cooperating shovel plates hinged together near their outer ends and means for swinging said shovel plates to move the material to be gathered laterally out of the path of movement of said base, and actuating means for said shovel plates comprising a pair of upper and lower arms having pivotal connection with said shovel plates.

7. In a mining machine of the character described, the combination comprising a portable base movable along a coal face, shovel mechanism mounted on the forward end of said base within the vertical limits of the latter comprising a pair of cooperating shovel plates hinged together near their outer ends and means for swinging said shovel plates to move the material to be gathered laterally out of the path of movement of said base, and actuating means for said shovel plates comprising a pair of upper and lower arms having pivotal connection with said shovel plates near the outer ends of said shovel plates.

8. In a mining machine of the character described, the combination comprising a portable base movable along a coal face, shovel mechanism mounted on the forward end of said base within the vertical limits of the latter comprising

a pair of cooperating shovel plates hinged together near their outer ends and means for swinging said shovel plates to move the material to be gathered laterally out of the path of movement of said base, and actuating means for said shovel plates comprising a pair of upper and lower arms having pivotal connection with said shovel plates near the outer ends of said shovel plates with their axis of pivotal connection coincident with said hinge pivot axis.

5. In a mining machine of the character described, the combination comprising a portable base movable along a coal face, and shovel mechanism mounted on the forward end of said base within the vertical limits of the latter comprising a pair of cooperating shovel plates hinged together near their outer ends and means for swinging said shovel plates to move the material to be gathered laterally out of the path of movement of said base, the outer ends of each of said shovel plates having a series of penetrating teeth.

10. In a mining machine of the character described, the combination comprising a portable base movable along a coal face, and shovel mechanism mounted on the forward end of said base within the vertical limits of the latter comprising a pair of cooperating shovel plates hinged together near their outer ends and means for swinging said shovel plates to move the material to be gathered laterally out of the path of movement of said base, the outer ends of each of said shovel plates having a series of penetrating teeth, and said teeth on said different plates being staggered so that the teeth on one plate may move within the spaces between the teeth on the other plate as said plates are swung about their pivots.

15. In a mining machine of the character described, the combination comprising a portable base movable along a coal face, shovel mechanism mounted on the forward end of said base within the vertical limits of the latter comprising a pair of cooperating shovel plates hinged together near their outer ends and means for swinging said shovel plates to move the material to be gathered laterally out of the path of movement of said base, and actuating means for said shovel plates comprising a pair of upper and lower arms having pivotal connection with said shovel plates and a pair of motor driven cranks respectively mounted near the top and bottom of said base and to which said arms are pivotally connected, for actuating the latter.

20. In a combined cutting and loading machine, the combination comprising a machine frame movable along a coal face, kerf cutting mechanism on said frame including a horizontally projecting kerf cutter for cutting a plane kerf in a coal seam inside the coal face, and material gathering means for gathering loose coal from the mine floor outside the coal face and arranged on said frame at the advancing end thereof and including a gathering element confined to horizontal movement back and forth across the front end of said frame, said gathering means being offset horizontally from said kerf cutter and said kerf cutter and gathering means being so arranged on the frame that they engage the coal to be acted upon thereby along parallel laterally adjacent paths and each operative to clear its path as the machine advances along the coal face, said horizontally movable gathering element moving the coal away from the side of said frame remote from the coal face.

13. In a combined cutting and loading machine, the combination comprising a machine frame movable along a coal face, kerf cutting mechanism on said frame including a horizontally projecting kerf cutter for cutting a plane kerf in a coal seam inside the coal face, and gathering mechanism arranged at the advancing end of the machine frame and including an oscillatory gathering device movable horizontally back and forth across the front end of said frame for gathering loose coal from the mine floor outside the coal face, said kerf cutter and said gathering mechanism being so arranged on said frame as to engage the coal acted on thereby concurrently along laterally adjacent paths and each operative to clear its path as the machine advances along the coal face.

14. In a mining and loading machine, the combination comprising a portable base movable along a coal face, kerf cutting means carried by said base comprising an elongated plane kerf cutter projecting horizontally from said base, and loading means carried by said base for gathering loose coal from the mine floor in advance of the base and for moving the loose coal laterally out of the path of movement of the base, said loading means including gathering and loading devices and said gathering and loading devices including cooperating, relatively movable, vertical shovel elements pivotally mounted on said base and swingable horizontally in advance of said base.

15. In a mining machine of the character described, the combination comprising a portable base movable along a coal face, and shovel mechanism mounted on said base comprising a pair of cooperating shovel elements mounted for pivotal movement on upright axes and hinged together near their outer ends, and means for swinging said shovel elements horizontally about their pivotal axes to move the material to be

gathered laterally out of the path of movement of said base.

16. In a reversible cutting and loading machine, the combination comprising a portable base movable along either of opposite coal faces, reversible coal cutting means mounted on said base including a kerf cutter swingable horizontally into a right angle position at either side of said base, and reversible shovel mechanism mounted on said base in a position offset horizontally from the active cutting portion of said kerf cutter, said shovel mechanism being automatically operative concurrently with the kerf cutting operation to move the loose coal from the mine floor in advance of the base laterally away from the coal face out of the path of movement of the base, said shovel mechanism being operative to effect its shoveling function irrespective of the coal face along which the machine is movable and including a reversely operative shovel element swingable horizontally across the advancing end of said base and said coal cutting means and said shovel mechanism acting concurrently to cut and load the coal along parallel paths as the machine advances along the coal face during either direction of cutting and loading.

17. In a mining machine of the character described, the combination comprising a portable base movable along a coal face, and shovel mechanism mounted on the forward end of said base comprising a pair of cooperating shovel elements mounted for pivotal movement and hinged together near their outer ends, a pair of cooperating guide elements pivotally mounted on said base and having sliding engagement with said shovel elements respectively, said shovel elements having guideways for respectively slidingly receiving said guide elements, and means for swinging said shovel and guide elements to move the material to be gathered laterally out of the path of movement of said base.

CERTIFICATE OF CORRECTION.

Patent No. 2,333,865.

November 9, 1943.

JOSEPH F. JOY.

It is hereby certified that error appears in the printed specification of the above numbered patent requiring correction as follows: Page 2, first column, line 42, for "suitable" read --suitably--; page 3, first column, line 42, for "lover" read --lower--; and that the said Letters Patent should be read with this correction therein that the same may conform to the record of the case in the Patent Office.

Signed and sealed this 25th day of January, A. D. 1944.

Henry Van Arsdale,
Acting Commissioner of Patents.
